UNITED STATES PATENT OFFICE.

PERCY JACKSON HIGGS, OF NEW YORK, N. Y.

DESIGN FOR A TABLE TOP.

Application filed June 11, 1921. Serial No. 476,937. Term of patent 3½ years.

To all whom it may concern:

Be it known that I, PERCY J. HIGGS, a citizen of the United States, and a resident of the city of New York, borough of Manhattan, in the county of New York and State of New York, have invented a new, original, and ornamental Design for Table Tops, of which the following is a specification, reference being had to the accompanying drawing, forming part thereof.

In the figure I have shown a table top having a border around its edge which includes a plurality of parallel lines and having a series of diamonds, clubs, hearts and spades alternately arranged around the border between certain of the parallel lines.

I claim:

The ornamental design for a table top, as shown.

PERCY JACKSON HIGGS.
